UNITED STATES PATENT OFFICE

DANIEL J. MAYER, OF BELLEVILLE, NEW JERSEY, ASSIGNOR TO METAL TEXTILE CORPORATION, OF WEST ORANGE, NEW JERSEY, A CORPORATION OF RHODE ISLAND

SCOURING IMPLEMENT

Application filed September 28, 1928. Serial No. 303,964.

This invention relates, generally, to an improved form and construction of scouring implement adapted to produce scraping, cleaning and polishing effects when applied to and 5 rubbed upon the surfaces of utensils or other surfaces desired to be cleansed.

The invention has for its principal object to provide a novel construction of implement, the operative head of which is made 10 of a knitted metallic fabric or of a composite fabric composed of textile yarn and metallic material, so combined with and supported by a holding means as to provide a spirally convolute body adapted to furnish, 15 at the working surface thereof, a series of spirally disposed projecting abrading convolutions, ridges or whorls having reduced clearance spaces therebetween.

The invention has for a further object to 20 provide a spirally convolute body or mass of abrasive metallic fabric formed on a comparatively rigid supporting core or retainer, whereby the novel desired convolute conformation of the body or mass is securely retained against the wear and tear of use; and, 25 furthermore, to provide a construction wherein in the metallic fabric is of a kind calculated to provide a great multiplicity of scraping edges or projections which, by reason of the 30 spirally convolute conformation given to the mass thereof in the finished article, are projected at the surface of the article in a great variety of angles and directions, so that, in the use of the article, a very efficient abrading 35 action is obtained no matter what may be the direction of movement imparted to the article when rubbing a surface to be cleaned therewith.

Other objects of this invention, not at this 40 time more particularly enumerated, will be clearly understood from the following detailed description of the same.

The invention is illustrated in the accompanying drawings, in which:—

45 Figs. 1 to 10 inclusive illustrate the mate-

rials from which the novel scouring implement is made and the manner in which said materials are assembled together to produce the novel finished article; and to this end, Fig. 1 shows a length of metallic abrasive fabric of the preferred kind, viz. a length of tubular knit fabric made from metallic wire; Fig. 2 shows how the initial length of fabric is folded lengthwise on itself to provide a suitable bulk thereof; Fig. 3 shows 50 how the retaining core is initially applied to the folded fabric, and how the corners of the latter are in-turned to produce neat end portions in the finished abrasive body; Fig. 4 is a detail cross section on line 4—4 in Fig. 3; Fig. 5 is a diagrammatic view illustrating 55 the manner in which the folded fabric material and the retaining core are intertwined together to produce the spirally convolute form of the finished body interlocked with 60 and supported by the retaining core; and Figs. 6 to 10 inclusive are sectional views to show various steps in intertwisting the abrasive fabric and retaining core together.

Fig. 11 is a side elevation of the finished 70 article in one general shape; and Fig. 12 is a face view of the finished article in another general shape.

Similar characters of reference are employed in all of the hereinabove described views, 75 to indicate corresponding parts.

In order to clearly illustrate the ultimate construction and essential characteristics of the finished article embodying the principles of the present invention, there is shown in 80 the drawings, in somewhat diagrammatic form, certain steps by which the finished article is evolved. The working head of the article is made from a metallic material, and preferably from a tubular knit metallic fabric comprising knitted metallic material of angular cross-sectional shape, such e. g. as flat ribbon-like copper or other metallic wire, such as shown in Kingman Patent No. 1,659,- 85 977, dated February 21, 1928; although other 90

forms of fabric having a component metallic material to provide abrasive elements may be employed if desired, such, for example, as a knitted or woven textile yarn material carrying a gimping of metallic wire, such as shown in Kingman Patent No. 1,501,784, dated July 15, 1924.

A length A of tubular knit metallic material, is flattened to provide a rectangular piece of suitable size (as shown in Fig. 1), is folded lengthwise upon itself to furnish an initial mass or body A' of substantial thickness (as indicated in Fig. 2). The corners B of the thus folded initial body A' are in 15 folded (as indicated in Figs. 3 and 5) to provide tapering closed end-portions C in the finished article, and a core element D of comparatively heavy metallic wire is doubled on itself into the U-shape shown in Fig. 3, and 20 disposed over the initial folded body in lengthwise straddling relation thereto.

After the core element D is thus applied to the initial folded body A', the straddling arms of the core element are mutually inter-twisted to form spirals d between which portions of the initial folded body are engaged and held; and at the same time the twisting of the core element arms in turn produces spirally convolute twists, rolls or folds of the 25 initial folded body along the length of the core element, whereby a plurality of spiral abrading ridges E are furnished with alternated or intermediate clearance spaces F of reduced cross-sectional diameter; the operations effecting this result being illustrated 30 more particularly in Figs. 5 to 10 inclusive of the drawings. The resultant convolute twists, rolls or folds forming the abrading ridges E are securely retained and supported 35 by the intertwined central core D which extends longitudinally or axially throughout the length of the working head of the finished article, and when using the article displacement or deformation of the abrading ridges 40 E is thus prevented, so that the article will last throughout a long life of usefulness.

Owing to the thickness of the folded initial body A' the abrading ridges E will be of substantial bulk, and consequently will each 45 provide a substantial area of contact surface when applied and rubbed over a surface to be scoured. The metallic material making the working head of the article, especially when made of knitted flat copper wire 50 or of a metal gimped textile fabric of the kind above referred to, will provide a great multiplicity of scraping elements formed by loops of the metallic material. Furthermore, 55 owing to the spirally convolute formation of the abrading ridges E, the scraping elements thus formed will be projected in many various directions so that some thereof will always be efficiently presented for their scraping 60 function no matter what the direction of 65

motion of the article may be when rubbed over the surface to be cleaned therewith.

The abrading ridges E will readily attack and scrape away encrustations desired to be removed from a surface undergoing cleaning or scouring operations, while the clearance spaces F intermediate the abrading ridges E will permit of escape of the loosened dirt particles. As a consequence of this mode of construction, the working head of the article is little likely to become filled up or clogged with loosened dirt, and such dirt as may enter the interstices of said working head will not be so tightly wedged or jammed therein, as not to be readily dislodged and 70 washed away by rinsing the article in water.

The article may be utilized in either the straight elongated form shown in Fig. 11, or may be provided in the ring-like form shown in Fig. 12. In either case, an end G 75 of the core element may be utilized as a shank for attaching the article to a handle stick (not shown) such as are commonly furnished in connection with disk mops and similar articles; the shank G in such case being inserted and secured in an end of a handle stick or otherwise fastened thereto.

As many changes could be made in the above described construction and many apparently widely different embodiments of 80 this invention could be made without departing from the scope thereof, it is intended that all matter contained in the above description or shown in the accompanying drawings shall be interpreted as illustrative and not 85 in a limiting sense.

I claim:—

1. A scouring implement comprising in combination, a core formed of a pair of wires intertwined from end to end, and a flattened tube of metallic fabric, knitted from metal strands, extending along, and held between, said wires and intertwined therewith to provide a series of spirally convolute abrading ridges having clearance spaces therebetween extending helically along and around said core, the loops of said fabric providing scraping projections where exposed at the surfaces of said abrading ridges.

2. A scouring implement comprising in combination, a core formed of a pair of wires intertwined from end to end, and a flattened body of metallic fabric having tapering end portions extending along, and held between, said wires and intertwined therewith to provide a series of spirally convolute abrading ridges having clearance spaces therebetween extending helically along and around said core, the converging end portions of the thus intertwined body providing the same with 110 tapered ends.

3. A scouring implement comprising in combination, a core formed of a pair of wires intertwined from end to end, and a flattened body of metallic fabric having tapering end 115

portions, knitted from metallic strands, extending along, and held between, said wires and intertwined therewith to provide a series of spirally convolute abrading ridges extending helically along and around said core, the loops of said fabric providing scraping projections where exposed at the surfaces of said abrading ridges, and the converging end portions of the thus intertwined flattened tube providing the same with tapered ends.

In testimony, that I claim the invention set forth above I have hereunto set my hand this 22nd day of September, 1928.

DANIEL J. MAYER.
